(57) **CLAIM**

The ornamental design for a powder particle weighing machine as shown and described.

DESCRIPTION

FIG. 1 is a front view of a powder particle weighing machine showing the claimed design;

FIG. 2 is a rear view thereof;

FIG. 3 is a left side view thereof;

FIG. 4 is a right side view thereof;

FIG. 5 is a plan view thereof;

FIG. 6 is a bottom view thereof;

FIG. 7 is a perspective view thereof;

FIG. 8 is a perspective view thereof with doors shown in an open position;

FIG. 9 is a front view of a main body of the powder particle weighing machine;

FIG. 10 is a back view of thereof;

FIG. 11 is a left side view of thereof;

FIG. 12 is a right side view of thereof;

FIG. 13 is a plan view thereof;

FIG. 14 is a bottom view thereof;

FIG. 15 is a perspective view thereof;

FIG. 16 is a front view a stocker of the powder particle weighing machine;

FIG. 17 is a rear view thereof;

FIG. 18 is a left side view thereof;

FIG. 19 is a right side view thereof;

FIG. 20 is a plan view thereof;

FIG. 21 is a bottom view thereof;

FIG. 22 is a perspective view thereof;

FIG. 23 is a front view of the powder particle weighing machine in a usage state; and,

FIG. 24 is a perspective view thereof in the usage state. The broken lines show portions of a powder particle weighing machine that form no part of the claimed design.

1 Claim, 24 Drawing Sheets
